R. P. MORRIS.
STANCHION OPERATING AND FASTENING MEANS.
APPLICATION FILED AUG. 11, 1917.

1,264,838.

Patented Apr. 30, 1918.

Inventor,
Robert P. Morris, by
G. C. Kennedy,
Attorney.

UNITED STATES PATENT OFFICE.

ROBERT P. MORRIS, OF WATERLOO, IOWA.

STANCHION OPERATING AND FASTENING MEANS.

1,264,838.

Specification of Letters Patent.

Patented Apr. 30, 1918.

Application filed August 11, 1917. Serial No. 185,777.

To all whom it may concern:

Be it known that I, ROBERT P. MORRIS, a citizen of the United States of America, and a resident of Waterloo, Blackhawk county, 5 Iowa, have invented certain new and useful Improvements in Stanchion Operating and Fastening Means, of which the following is a specification.

My invention relates to improvements in 10 stanchion operating and fastening-means, and the objects of my improvements are:

First, to provide easily engaged and separable fastening-means for the hinged standards of a stanchion, and

15 Second, to supply mechanism adapted to simultaneously draw them together or separate from each other the hinged standards of a plurality of such stanchions.

These objects I have accomplished by the 20 means which are hereinafter described and claimed, and which are illustrated in the accompanying drawings, in which Figure 1 is an elevation of a plurality of stanchions and their supporting-means, with their separable fastenings, and the mechanism for simultaneously actuating the movable standards of all the stanchions, and Fig. 2 is a perspective view, in detail of said fastenings and operative connections between the standards of the stanchions.

Similar numerals of reference denote corresponding parts throughout the several views.

In the drawings, the numeral 26 denotes a 35 solid base in which are embedded the lower ends of a plurality of posts 30, whose upper ends have clamping-members 27 in which are supported cross-beams 29 of tubular form. Certain of the clamping-members 27 40 have brackets 28 provided with horizontal bearing orifices to receive a rotatable shaft 31, on one end of which is mounted a hand-wheel 32. Between posts 30, clamping-members 8 are fixed medially on the cross-beams 29, and have horizontally orificed spaced 45 brackets 9 through which said shaft 31 passes, winding-drums 10 being fixedly mounted on said shaft between said brackets. In each case, one of the clamping-members 50 has a depending integral ring 7 in which is positioned a vertically movable tubular body 4, provided with an external annular flange 6 which rests upon said ring 7. The body 4 has a rectangular notch 5 in its 55 lower edge, for a purpose to be described.

Between each pair of posts 30, and im-

mediately below the tubular body 4 is a stanchion composed of two like standards 1 and 2, whose lower ends are hinged together at 23, the hinge-connection being 60 linked to the base-body 26 by means of a chain 24, and eye-bolt 25 embedded in the base-body.

The tubular body 4 has a fixed arm 3 which is secured to and projects inwardly 65 and upwardly from the upper end of the standard 2. A chain 11 has one end secured to the drum 10 to be wound thereon, and depends through the tube of the body 4, and carries at its lower end a catch 13, 70 consisting of a plate having a pair of upwardly-extending lugs 12 connected by a pintle, the latter secured within the lowest link of said chain. Said plate or catch 13 has an upwardly extending boss 19 adapted 75 to be received within the notch 5 of said body 4, and also has a laterally extending part 14 containing a rectangular orifice 20.

Upon spaced lugs 17 on the upper part of the other standard 1, which in this case is 80 shown as made from channel-bar, but may be constructed of any other desired section, is pivoted medially on a pintle 21 a latch 16 having a detent adapted for engagement with the orifice 20 in the catch 13, said latch 85 having its opposite end elongated into a finger-piece 22, a coiled spring 18 being engaged between said finger-piece and said standard to yieldingly propel the other end of the latch and its detent downwardly to 90 tend to keep it from disengagement from said catch 13.

The numeral 15 denotes an inclined slide-way body mounted on the upper end of said standard 1, projecting therefrom, and receiving the catch-end slidably to guide it under the detent on said latch when the standards are swung together into closed position.

When the standard 1 is swung toward the other standard 2, the chain 11 being wound 100 up so that the catch 13 is in its uppermost position with its boss 19 engaged with the notch 5 in the body 4, the projecting part 14 of said catch is received under the latch 16, sliding over the guide body 15, lifting 105 the latch until the detent drops into the orifice 20 where it is held securely by means of the spring 18, but may be disconnected by depressing the finger-piece 22 manually.

In the event that it is desired to separate 110 the standards of all the stanchions simultaneously, the hand-wheel 32 and shaft 31

may be rotated to cause the chains 11 to unwind from the drums 10. This lowers the catches 13 out of engagement with the tubular bodies 4, so that the gravity of the standard 1 may act in swinging the standard outwardly and downwardly to a position shown in dotted lines in said Fig. 1, without disengaging the catch from said latch 16.

In rotating the drums reversely, the chains 10 are again wound up, thus restoring the catch to its position of engagement with the body 4, while closing the standard 1 toward the standard 2 in each case. Since the tubular body 4 may rock horizontally relatively to said ring 7 upon which it is supported, the stanchion as a whole, may freely swing in all directions, and may have a limited movement upwardly because of the sliding fit of the body in said ring.

Having described my invention, what I claim as new and desire to secure by Letters Patent, is:

1. In combination, supporting means, a shaft rotatably mounted thereon, a stanchion composed of spaced standards hinged together at their lower ends, resiliently-controlled engaging-means on one of said standards, a catch adapted for releasable engagement with said engaging-means, a bearing 25 on said supporting-means, a tubular body on the other standard movable in said bearing and having engaging-means, said catch having engaging-means adapted for releasable engagement with the engaging-means on said tubular body, and a flexible connection between said catch and said shaft passed through said tubular body to be wound upon said shaft.

2. In combination, supporting means, a 40 shaft rotatably mounted thereon, like stan-

chions positioned below said shaft, each stanchion composed of spaced standards hinged together at their lower ends, engaging-means on one of said standards, a catch adapted for releasable engagement with said engaging-means, and a flexible connection between said catch, the other of said standards and said shaft, adapted to be wound up on the shaft, whereby when said flexible connection is so wound up, the catch being engaged with the engaging-means on the first-mentioned standard, said standards are closed together.

3. In combination, supporting means, a shaft rotatably mounted thereon, like stanchions positioned below said shaft, each stanchion composed of spaced standards hinged together at their lower ends, engaging-means on one of said standards, a catch 55 adapted for releasable engagement with said engaging-means, a bearing on said supporting-means, a tubular body on the other standard movable in said bearing and having engaging-means, said catch having engaging-means adapted for releasable engagement with the engaging-means on said tubular body, and a flexible connection between 60 said catch, movable through said tubular body to be wound upon said shaft, whereby when the shaft is rotated in one direction, the catch being engaged with the engaging-means on the first-mentioned standard, the standards are closed together and the engaging-means on said catch engaged with the 65 engaging-means on said tubular body, locking them together releasably.

Signed at Waterloo, Iowa, this 26th day of July, 1917.

ROBERT P. MORRIS.
